SAFETY DEVICE FOR FLUID POWER
OPERATED PRESSES

Howard L. Carlyle, West Allis, Wis., assignor to
Cutler-Hammer, Inc., Milwaukee, Wis., a cor-
poration of Delaware

Application November 22, 1943, Serial No. 511,331

7 Claims. (Cl. 192—134)

This invention relates to a safety device for a fluid power operated press.

A primary object is to provide a simple and reliable safety control mechanism for a press of the aforementioned character.

Another object is to provide a safety device for such a press whereby the hands of the operator are left free to manipulate the work material while positively insuring against injury to the hands of the operator during the power stroke of the press.

Another object is to provide a press control system including a normally open foot-operated switch whereby initiation and normal termination of the pressing operation may be effected.

Another object is to provide a press member having at least two relatively movable parts the relative movement of which may be utilized to effect a safety control function under given abnormal conditions.

Another object is to provide for use of a plurality of electric switch elements which are so arranged with respect to each other and to the press parts as to distinguish between normal and abnormal conditions in the operation of the press.

Another object is to provide for adjustment of certain of said switch elements to correspond to the thickness of the particular material being worked upon.

Another object is to provide for adjustment of the position of a switch element automatically in response to the thickness of the work material as an incident to the initial operation of the press.

Another and more specific object is to provide for use of such a safety device in conjunction with a spot welding machine.

Other objects and advantages of the invention will hereinafter appear.

The accompanying drawing illustrates somewhat schematically and diagrammatically an embodiment of the invention, it being understood that the embodiment illustrated is susceptible of modification in respect of certain structural details thereof without departing from the scope of the appended claims.

In the drawing, the single figure illustrates a press having my novel safety control mechanism applied thereto.

Referring to the drawing, the numeral 5 designates a fragment of a cylinder of a known type of press; said cylinder having therein a plunger (not shown) the movement of which toward its upper and lower extreme positions is effected by the application of fluid pressure to the lower and

upper ends thereof respectively. The means for controlling the admission to and release of fluid pressure from said opposite ends of the piston may comprise a suitable or known form of multi-way valve (not shown) which may be housed within an auxiliary casing such as that shown in dotted lines at 6. In practice said valve is biased to a position wherein the fluid pressure is controlled in a manner to force the aforementioned piston to its upper extreme position within cylinder 5, so that the parts associated with the piston will be in the normal positions thereof shown in the drawing.

More particularly, the shaft 7 carried by and extending downwardly from the piston has rigidly attached thereto an L-shaped bracket 8; the latter in turn having attached thereto an inwardly extending contact member or plate 9 which is insulated from bracket 8 as by means of an insulating spacer 10. Plate 9 has attached thereto a pair of upwardly and downwardly facing contact tips 11 and 12, which tips preferably consist of silver or a suitable composition including silver.

Shaft 7 is preferably provided with a portion 13 of reduced cross sectional dimensions and a head or end flange portion 14. Slidably mounted upon portions 13 and 14 is an auxiliary press member 15, the upper end portion 16 of which is recessed as shown at 17 to accommodate the flange portion 14 and is provided with an opening 18 to accommodate the aforementioned portion 13. The inwardly extending flange 19 cooperates with flange portion 14 to limit the degree of downward movement of auxiliary press member 15 with respect to shaft 7. In practice member 15 will assume its illustrated position with respect to shaft 7 by the force of gravity, but I prefer to interpose between the lower wall 40 of recess 17 and the lower surface of flange portion 14 a relatively light coiled compression spring 20; a counterbore 21 being preferably provided in said lower surface of flange portion 14 to accommodate and center the upper end of said spring. Although I have shown more or less diagrammatically the lost motion interlocking connection between shaft 7 and auxiliary press member 15, it is to be understood that the arrangement is such as to prevent accidental complete separation of the latter from the former; whereas obviously suitable provision (such as means for removably attaching flange 19 to member 15) may be made for enabling separation of these parts at will.

The portion 16 of auxiliary press member 15

has attached thereto a laterally extending lug 22 which carries a contact plate 23 having a tip 24 of silver or a composition containing silver; plate 24 being suitably insulated from lug 22, as indicated at 25. The arrangement is such that in the illustrated normal or fully extended position of auxiliary member 15 with respect to shaft 7 the contact tip 24 will be engaged under suitable pressure with the aforementioned contact tip 11. This presets an energizing circuit for the valve operating winding 26 for completion upon closure of a normally open foot-operated switch 27. Said circuit may be traced from line L¹ through switch 27 (when closed), conductor 29 through winding 26, conductor 30 to plate 9, contact tips 11 and 24, plate 23, and by conductor 31 to line L².

Winding 26 when thus energized effects operation of the valve in a well known manner to release the fluid pressure applied to the lower end of the piston and to simultaneously apply the desired value of the fluid pressure to the upper end of the piston, whereby downward movement of shaft 7 is effected.

With the parts as thus far described the arrangement is such that during downward movement of auxiliary press member 15 (along with shaft 7) as an incident to closure of switch 27, as soon as the lower or working surface 32 of member 15 engages an obstruction, such as work material 33 interposed between the same and the upper surface of the lower or stationary die member 52, member 15 will remain stationary and shaft 7 will move downwardly with respect thereto. This will result in separation of contact tip 11 from tip 24 to interrupt the aforescribed energizing circuit of winding 26, with consequent return of said parts to the initial positions thereof illustrated.

To avoid the effect, under normal conditions, of such operation of the aforescribed parts, I provide a contact plate 34 which is initially positioned as shown in dotted lines, so that the contact tip 35 carried thereby will be engaged by contact tip 12 when the lower end or surface 32 of auxiliary press member 15 is a substantial distance above the work material 33. Such distance may in practice be greater than the thickness of a hand or finger of an operator, only during the initial operation of the press, and is variable in accordance with the thickness of the particular work material, such as 33, to be operated upon. In this initial operation of the press, for each different thickness of material to be operated upon, it will be apparent that contact tip 11 will remain in engagement with contact tip 24 until after contact tip 12 has engaged contact tip 35. Such engagement of tip 12 with tip 35 provides an energizing circuit for winding 26, which circuit may be traced from plate 9 through contact tips 12 and 35 and plate 34, and through conductor 36 to line L². It follows that the energizing circuit for winding 26 will be maintained notwithstanding disengagement of contact tip 11 from contact tip 24 due to engagement of auxiliary press member 15 with the work material 33.

As shown plate 34 is carried by but insulated, at 37, from a metal member 38 which is pivotally supported at 39 upon a member 40. Member 40 is provided with a forwardly extending portion between which and member 38 a coiled compression spring 42 is interposed to bias member 38 toward its upper extreme position with respect to member 40; the latter being provided with a

laterally extending lug 43 overlying member 38 to limit such upward movement thereof. Portion 41 of member 40 is also provided with a lug 44 underlying plate 34 to limit downward movement of member 38 with respect to member 40, such downward movement of member 38 being effected against the aforementioned bias of spring 42.

Member 40 is pivotally supported at 45, and the same is manually moved to its upper extreme position, shown in dotted lines, prior to the initial operation of the press. The pivotal portion of member 40 is provided with an enlargement having an arcuate edge portion 46 against which a friction-clutch member 47 is adapted to bear, 15 said enlargement of member 40 having a shoulder 48 formed at the upper end of arcuate edge 46 for cooperation with member 47 to limit manual upward movement of said member 40. A coiled compression spring 49 is interposed between a 20 suitable stationary abutment 50 and member 47 to provide for frictional retention of member 40 in any position to which it may be moved.

From the foregoing description it will be apparent that during the initial operation of the 25 press (the member 40 and plate 34 being initially in the respective dotted line positions thereof illustrated) the full downward stroke of shaft 7 (as modified only by the thickness of the particular work material 33) will be insured. The corresponding downward movement of contact tip 12 will (by engagement thereof with contact tip 35) first take up the lost motion provided between members 38 and 40, and thereafter effect downward movement of the latter about its pivot 45 30 against the yieldable restraint afforded by friction clutch member 47. During such automatic downward movement of member 40 the shaft 7 will move downwardly to effect engagement of auxiliary member 15 with the work material 33 35 and to thereafter take up the lost motion provided between the lower end 14 of said shaft 7 and said auxiliary member 15. It follows that the final adjustment of member 40 thus automatically effected is definitely proportional to, or 40 related to, the thickness of the particular work material 33.

More particularly, such automatic adjustment of the position of member 40 is such that when the press parts are returned to their normal or 45 inactive positions illustrated by re-opening of foot-operated switch 27, the contact tip 35 will assume a position which is a distance beneath contact tip 12 only slightly less than the distance between the lower end 32 of auxiliary member 15 and the upper surface of the work material 33. Thereafter if the operator's hand or finger is accidentally or otherwise interposed between the upper surface of the work material 33 and the lower end 32 of member 15 the downward movement 50 of member 15 will be stopped and then upon a slight degree of further downward movement of shaft 7 relatively thereto contact tip 11 will be disengaged from contact tip 24, thus immediately deenergizing winding 26 whose associated 55 valve then moves to its normally biased position to not only prevent any further downward movement of shaft 10 under the action of the fluid pressure, but said valve when so permitted to return to its normal position insures return of shaft 7 and the parts associated therewith to the normal positions thereof illustrated.

In practice the initial operation of the press will be effected by the operator or by a supervisor with extreme care to insure against injury to the hands or fingers; such initial operation

embodying the simplest method of effecting automatic adjustment of member 40 in direct accordance with the thickness of the material (such as 33) to be operated upon. I appreciate the fact, however, that the member 40 might be pre-adjusted manually in accordance with the thickness of the particular work material; and for this purpose a suitable scale and pointer arrangement of legends might be provided upon the adjacent parts of member 40 and clutch member 47, respectively, whereby the safety feature is provided for the initial operation of the press. - I prefer to employ the method of operation first described whereby adjustment of member 40 is effected automatically by an initial operation of the press; such method being more positive and fool-proof in respect of insuring against injury to an operator.

As shown member 47 is preferably provided with a stud or projection 51 to fit within one end of spring 49 to insure maintenance of said parts in proper relationship to each other.

The safety control device herein disclosed is well adapted for use with the press parts of an electric spot welding machine. In such a machine the work-engaging press parts corresponding to those shown at 32 and 34 will preferably be in the form of points or cones, as is well understood in the art. Also, in such a spot welding machine it is usual to provide a normally open switch responsive to the development of a predetermined degree of pressure of the welding electrodes (corresponding with members 32 and 33) against the work material to effect closure of such switch for supplying the desired value of welding current to such electrodes. Moreover, the voltage of the welding current normally employed with such electrodes, is so low as to prevent any possibility of substantial shock or other injury to an operator.

I claim:

1. In combination, a pair of relatively movable press members initially substantially spaced from each other, one of said members comprising two parts having a straight line lost motion connection affording a predetermined degree of telescopic movement therebetween, one of said parts being normally biased into an extended relationship to the other, fluid power operated means subject to manual control for initiating movement of said two-part member toward work material interposed between the same and the other member, associated means responsive to relative movement of said parts of said two-part member due to the presence of a foreign object of substantial thickness between the same and the work material to substantially instantaneously stop such movement of said two-part member, said last mentioned means including a set of electrical switch contacts carried by said two-part member and bodily movable with the latter, said contacts being normally engaged with each other, and the same being disengageable as an incident to the aforementioned relative movement of said parts due to presence of such foreign object to effect interruption of an electric circuit controlled thereby, for the purpose set forth.

2. In combination, a pair of relatively movable press members initially substantially spaced from each other, one of said members comprising two parts having a straight line lost motion connection affording a predetermined degree of telescopic movement therebetween, spring means interposed between said parts to

normally bias one of the same into an extended relationship to the other, fluid power operated means subject to manual control for initiating movement of said two-part member toward work material interposed between the same and the other member, associated means responsive to relative movement of said parts of said two-part member due to the presence of a foreign object of substantial thickness between the same and the work material to substantially instantaneously stop such movement of said two-part member, said last mentioned means including a set of electrical contacts carried by the respective parts of said two-part member and bodily movable with the latter, said contacts being normally engaged with each other, the same being disengageable as an incident to the aforementioned relative movement of said parts to effect interruption of an electric circuit controlled thereby, for the purpose set forth, and an additional contact associated with said set of contacts and adapted to be engaged by one of the latter prior to separation of the contacts of said set in the normal operation of said press members, whereby said electric circuit is maintained notwithstanding separation of the contacts of said set.

3. In combination, a pair of relatively movable press members initially substantially spaced from each other, one of said members comprising two parts having a straight line lost motion connection affording a predetermined degree of telescopic movement therebetween, one of said parts being normally biased into an extended relationship to the other, fluid power operated means subject to manual control for initiating movement of said two-part member toward work material interposed between the same and the other member, associated means responsive to relative movement of said parts of said two-part member due to the presence of a foreign object of substantial thickness between the same and the work material to substantially instantaneously stop such movement of said two-part member, said last mentioned means including a set of electrical contacts carried by the respective parts of said two-part member and bodily movable with the latter, said contacts being normally engaged with each other, the same being disengageable as an incident to the aforementioned relative movement of said parts to effect interruption of an electric circuit controlled thereby, for the purpose set forth, an additional contact association with said set of contacts and adapted to be engaged by one of the latter prior to separation of the contacts of said set in the normal operation of said press members, whereby said electric circuit is maintained notwithstanding separation of the contacts of said set, and means including said one of said set of contacts for automatically effecting adjustment of the position of said additional contact in accordance with the thickness of the aforementioned interposed work material.

4. In combination, a pair of relatively movable press members, one of said members comprising at least two parts having a straight line lost motion connection affording a predetermined degree of telescopic movement therebetween, one of said parts being normally biased into an extended relationship to the other, fluid power operated means for effecting movement of said two-part member toward work material interposed between the same and the other member, electrical means including a foot-operated switch adapted when closed to render said power operated means ef-

fective, whereby the hands of an operator are freed for manipulation of the work material, associated means including a pair of normally closed electrical switch contacts carried by said two-part member and bodily movable with the latter, said contacts being separable automatically upon telescopic movement of said one part with respect to the other against said bias due to the presence of the operator's hand between one of the press members and the work material, and said contacts when separated under such conditions acting to instantaneously render said power operated means ineffective, whereby further movement of said two-part member toward the work material is stopped.

5. In combination, a pair of relatively movable press members, one of said members comprising at least two parts having a straight line lost motion connection affording a predetermined degree of telescopic movement therebetween, means including a relatively weak spring interposed between said parts to normally bias one of the same into an extended relationship to the other, fluid power operated means for effecting movement of said two-part member toward work material interposed between the same and the other member, electrical means including a foot-operated switch adapted when closed to render said power operated means effective, whereby the hands of an operator are freed for manipulation of the work material, associated means including a pair of normally closed electrical contacts respectively carried by the parts of said two-part member and bodily movable with the latter, said contacts being separable automatically upon telescopic movement of said one part with respect to the other against said spring bias due to the presence of the operator's hand between one of the press members and the work material, said contacts when separated under such conditions acting to instantaneously render said power operated means ineffective, whereby further movement of said two-part member toward the work material is stopped, and means including a third electrical contact cooperable with one contact of said pair to render the latter when separated ineffective for stopping such movement of said two-part member.

6. In combination, a pair of relatively movable press members, one of said members comprising at least two parts having a straight line lost motion connection affording a predetermined degree of telescopic movement therebetween, one of said parts being normally biased into an extended relationship to the other, fluid power operated means for effecting movement of said two-part member toward work material interposed between the same and the other member, electrical means including a foot-operated switch adapted when

closed to render said power operated means effective, whereby the hands of an operator are freed for manipulation of the work material, associated means including a pair of normally closed electrical contacts carried by said two-part member and bodily movable with the latter, said contacts being separable automatically upon telescopic movement of said one part with respect to the other against said bias due to the presence of the operator's hand between one of the press members and the work material, said contacts when separated under such conditions acting to instantaneously render said power operated means ineffective, whereby further movement of said two-part member toward the work material is stopped, and means including a third electrical contact cooperable with one contact of said pair to render the latter when separated ineffective for stopping such movement of said two-part member, said last mentioned contact being adjustable automatically by said one contact of said pair in accordance with the thickness of the work material as an incident to the initial normal cycle of operation of said press members with respect to the work material, whereby subsequent effectiveness of said pair of contacts under the aforementioned abnormal conditions is insured.

7. In combination, a pair of relatively movable press members initially substantially spaced from each other, one of said members comprising two jointly movable parts having a straight line lost motion connection affording a predetermined degree of telescopic movement therebetween, one of said parts being normally biased into an extended relationship to the other, a pair of normally closed contacts carried by said two-part member and bodily movable with the latter, a normally open foot-operated switch included in a circuit in series with said contacts whereby said circuit is subject to control by said switch and said contacts jointly, fluid power means operable upon completion of said circuit for effecting relative movement of said members to effect pressure engagement thereof with work material interposed therebetween, said one of said parts when engaged with the work material being adapted to effect opening of said contacts, thereby tending to interrupt said electric circuit, for the purpose set forth, and a third contact cooperable with one contact of said pair to provide for maintaining said circuit under normal conditions, the position of said third contact being automatically adjustable directly in accordance with the thickness of the work material, whereby effectiveness of said pair of contacts to interrupt said circuit under abnormal conditions is insured.

HOWARD L. CARLYLE.
